Simulated bowling game backstop, including a runway, a hood, and a plurality of playing pieces.

UNITED STATES PATENT OFFICE

2,512,516

SIMULATED BOWLING GAME BACKSTOP

Horace Bluford, Virginia Beach, Va.

Application January 27, 1949, Serial No. 73,108

2 Claims. (Cl. 273—53)

1

This invention relates to new and useful improvements and structural refinements in games, and the principal object of the invention is to provide apparatus for a game wherein a rolling projectile similar to a billiard ball is forcibly propelled by means of a cue so as to upset a plurality of upstanding playing pieces in the form of miniature bowling pins.

This object is achieved by the provision of a runway similar to a bowling alley, one end portion of this runway constituting what may be referred to as a target region on which the playing pieces are positionable, and an important feature of the invention resides in the provision of a hood which is swingable forwardly and rearwardly over the target region so that when it is in its forwardly swung position it protective- 5 ly segregates this region from the remaining portion of the runway and not only indicates to the players that they should abstain from propelling the projectile when upset playing pieces are being erected, but also, the hood in its forwardly swung position effectively safeguards the person erecting the playing pieces from possible injury by an accidentally or unintentionally propelled projectile.

Moreover, when the hood is in its rearwardly swung position it constitutes a deflector not only for the projectile, but also for the upset playing pieces which, in the absence of the hood, would 30 inevitably become scattered from the runway and possibly cause injury to bystanders.

Another feature of the invention involves the formation of a sight opening in the hood, whereby the person designated to erect upset playing pieces may observe the movement of the players, regardless of whether the hood is in its forwardly or rearwardly swung position.

A still further feature of the invention resides in the provision of side guards which extend forwardly from the hood along a portion of the runway and consequently prevent lateral dispersion of the projectile and playing pieces in regions of the runway which are not protected by the hood.

Some of the advantages of the invention reside in its simplicity of construction, in its highly entertaining nature, and in its adaptability to economical manufacture.

With the above more important objects and features in view and such other objects and features as may become apparent as this specification proceeds, the invention consists essentially of the construction and arrangement of parts

as shown in the accompanying drawings in which:

Figure 1 is a longitudinal cross sectional view of the invention;

Figure 2 is a cross sectional view, taken substantially in the plane of the line 2—2 of Figure 1;

Figure 3 is a fragmentary cross sectional view showing the rear end portion of the subject illustrated in Figure 1, but with the hood in its forwardly swung position;

Figure 4 is a cross sectional view, taken substantially in the plane of the line 4—4 of Figure 1; and

Figure 5 is a fragmentary end view, taken in the direction of the arrow 5 in Figure 1.

Like characters of reference are employed to designate like parts in the specification and throughout the several views.

Referring now to the accompanying drawings in detail, the invention consists of a game apparatus designated generally by the reference character 10, the same embodying in its construction a runway or alley 12 assuming the form of a substantially U-shaped trough or channel and including a bottom 14, a pair of spaced, longitudinal side rails 16, and a playing strip 18 which is somewhat narrower than the bottom 14 so that the longitudinal edges of the strip 18 are spaced from the side rails 16 to form a pair of longitudinally extending side channels 20 which are "out of bound" and are not intended to be used when the game is properly played.

The side rails 16 extend downwardly beyond the bottom 14 as indicated at 22 and are reinforced by a plurality of cross members 24 equipped with pairs of suitable legs 26 whereby the entire apparatus is supported, as will be clearly apparent.

The side rails 16 at the forward end of the runway 12 are mutually convergent as at 28 but are spaced apart so as to provide an opening 30 whereby access may be had to the runway strip 18 for the purpose of forcibly propelling a spherical projectile 32 (see Figure 1) similar to a billiard ball by means of a cue 34 along the strip 18 toward

a set of movable playing pieces 36 which are similar to but smaller than conventional bowling pins and which are positioned on the rear end portion of the runway strip 18 which constitutes what may be referred to as the target region 38.

A suitable arrow 40 may be inscribed or painted on the playing strip 18 for obvious reasons, and it will be observed that the rear end portion of the runway 12, beyond the terminus of the playing

strip 18, is provided with a pit 42 which, in turn, communicates with a downwardly inclined return chute 44 through which a projectile may gravitate into a storage trough 46 located at the forward end of the apparatus (see Figure 1).

When the game is played, the projectile 32 propelled by the cue 34 is intended to travel along the playing strip 18 and impact the playing pieces 36, the score being computed, of course, by the playing pieces which are upset. The "out of bound" channels 20 communicate with the pit 42, so that if the projectile deviates laterally from the playing strip 18 and travels through either of the channels 20 into the pit 42, no score is counted. Since the upset playing pieces may fall into the pit 42, means are provided for preventing such upset pins from blocking the chute 44, these means involving the provision of a swingable closure 48 which is pivotally mounted in the chute adjacent the pit 42 on a transverse shaft 50 and a suitable spring (not shown) is employed for normally retaining the closure in its closed position to prevent the playing pieces 36 from falling into the chute 44. However, when it is desired to return a projectile through the chute 44 to the trough 46, the closure 48 is manually depressed when the projectile is inserted into the chute, as will be clearly apparent.

In addition to the players of the game, one person is designated to erect the upset playing pieces 36 and to return the projectile from the target region 38 through the chute 44, this person being stationed, of course, at the rear end portion of the apparatus.

The essence of novelty in the invention resides in the provision of a swingable hood 52 which is positioned above the target region 38 and embodies in its construction a pair of spaced sector-shaped plates 54 which are pivoted at the apices thereof by means of suitable pins or screws 56 to a pair of upright posts 58 which, in turn, are secured to the outer surfaces of the runway side rails 16 by additional screws 60. For purposes of reinforcement, suitable straps 62 may be provided on the inner surfaces of the side rails 16 and may be secured in position by the same screws 60, the straps 62 coacting with the posts 58 to provide bearings for the aforementioned pivot pins or screws 56, as will be clearly apparent.

The hood 52 also includes in its construction a convexo-concave wall 64 which connects together the arcuate edges of the side plates 54, the wall 64 being equipped with outturned front and rear edges or flanges 66, 68 respectively, as will be clearly apparent.

When the hood 52 is in its rearwardly swung position as indicated in Figures 1, 2 and 4, it constitutes an effective deflector which prevents the playing pieces 36 and the projectile 32 from scattering when the playing pieces are impacted by the projectile. It is to be noted that in this position, the flange 68 of the hood 52 rests upon the rear end rail 70 of the runway 12, while the front flange 66 of the hood is upstanding as is best shown in Figure 4, thus providing a surface on which may be inscribed suitable rules for playing the game.

Since the runway 12 is disposed at such level that the hood 52 extends above the head of the attendant at the rear of the apparatus, the wall 64 is provided with a transversely elongated sight opening 72, disposed substantially at eye level when the hood is swung either forwardly or rearwardly, thus enabling the attendant to observe,

in either position of the hood, the movements of the players.

The wall 64 is also equipped adjacent the opening 72 with a handle 74 whereby the entire hood 52 may be swung to its forward position wherein the front flange 66 of the hood rests upon the upper edges of the side rails 16, as is indicated in Figure 3. In this position the hood 52 protectively segregates the target region 38 from the remaining portion of the runway 12 and the front surface of the back flange 68 may be inscribed with a suitable legend to warn the players that upset playing pieces are being erected and, therefore, to abstain from the use of the projectile.

In order to safeguard against the possibility of the projectile or playing pieces from leaving the runway strip 18 before such dispersion could be prevented by the hood 52 in its rearwardly swung position, a pair of side guards 76 are provided, 10 each of these assuming the form of a triangular net provided at the diagonal side thereof with a tubular sleeve or hem 78 which, in turn, is threaded on a diagonal rod 80 which has one end thereof secured as at 82 to the side rails 16 while its remaining end is secured as at 84 to the posts 58. It should, of course, be understood that two of the rods 80 are provided, one at each side of the runway, and the remaining sides or edges of the guards 76 are suitably attached as at 86, 88 to the side rails 16 and posts 58, respectively, as will be clearly apparent. (See Figure 1.)

For sake of clarity, the guards 76 and rods 80 have not been illustrated in Figures 2, 3, 4 and 5 of the drawings.

It is believed that the advantages and use of the invention will be clearly understood from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a game apparatus, the combination of an elongated runway having front and rear ends and including a playing strip which extends longitudinally to a point spaced forwardly from the rear end of the runway, a pit provided between the rear end of the runway and the rear end of said playing strip, a rear end portion of said strip affording a target area disposed forwardly of said pit, a pair of coaxial fulcrum elements provided at opposite sides of said runway and having a transverse axis disposed substantially at the forward end of said target area, and a hood including a pair of transversely spaced sector-shaped plates having their apex portions mounted on the respective fulcrum elements, each plate having an outer edge and two radial edges of a length substantially equal to the distance of said fulcrum elements from the rear end of the runway, and an outer wall having its opposite side edges connected to the outer edges of the respective plates, said hood being swingable from a rearward position wherein the outer wall thereof extends over said target area and said pit to a forward position wherein said outer wall is disposed above said runway forwardly of the target area to separate the latter from the remainder of said playing strip.

2. The device as defined in claim 1 wherein said runway is disposed at such level that said hood extends above the head of a player at the rear end of the runway, and wherein the outer wall of said hood is provided with a transversely elongated sight opening disposed substantially at the level of the stated player's eyes when the hood is either in its forwardly or rearwardly swung position.
